UNITED STATES PATENT OFFICE.

WILLIAM ARCHER BORUM, OF JACKSON, MISSISSIPPI.

LAWN-SWING.

1,056,145.

Specification of Letters Patent. Patented Mar. 18, 1913.

Application filed November 10, 1911. Serial No. 659,651.

To all whom it may concern:

Be it known that I, WILLIAM A. BORUM, a citizen of the United States, residing at Jackson, in the county of Hinds and State of Mississippi, have invented a new and useful 5 Lawn-Swing, of which the following is a specification.

The present invention aims to provide, in a swing comprising oppositely disposed 10 chairs, movably mounted backs for the chairs, which backs may be placed in parallelism with the seats of the chairs, to form a couch.

A further object of the invention is to provide 15 a swing having oppositely disposed chairs, the backs of which may readily be reversed, and be lowered into parallelism with the seats, to form a couch.

With the foregoing and other objects in 20 view, which will appear as the description proceeds, the invention resides in the combination and arrangement of parts and in the details of construction hereinafter described and claimed, it being understood 25 that changes in the precise embodiment of invention herein disclosed can be made within the scope of what is claimed without departing from the spirit of the invention.

In the accompanying drawings,—Figure 30 1 shows the invention in side elevation; Fig. 2 is a top plan; Fig. 3 is a side elevation, showing the backs of the chair portions of the swing disposed in couch-forming position; and Fig. 4 is a fragmental side elevation, showing one of the backs reversed 35 from the position shown in Fig. 1.

In carrying out the invention there is provided a supporting structure comprising a frame 1, the frame 1 including side bars 40 2, connected by slats 3, certain of which, denoted by the numeral 4, are removable, the slats 4 being adapted to rest in notches 5 in the side bars 2 of the frame 1. The supporting structure further includes suspension 45 members 6, preferably taking the form of bars, united by means of pivot elements 7 with the frame 1, the supporting members 6 being adapted for connection with an overhead support.

50 The pivot elements 7 are connected with the lower ends of back supports 8, ordinarily taking the form of bars, these back supports 8 being equipped with longitudinally extended slots 9. The back supports 8 55 constitute parts of connected, oppositely disposed chairs, each chair including a seat

10, connected with one suspension member 6, as shown at 11, the seat 10 being connected likewise with the back support 8 as shown at 12. The invention, if desired, may include 60 tie bars 14, connected as shown at 15 with the suspension members 6, and as shown at 16, with the back supports 8. The seats 10 carry upon their rear edges, stops 20, having functions which will be set forth 65 hereinafter.

Each chair includes a back, denoted generally by the numeral 21. Upon one face, the back 21 is upholstered, as shown at 22, and upon the other, opposite face, the back is 70 slatted, or otherwise fashioned to withstand hard usage, as shown at 23. It is to be understood that the chair includes a pair of the back supports 8, and between these back supports 8 of the chair, the back 21 is mounted for sliding movement longitudinally of the back supports, and for pivotal movement with respect to the back supports. To effect this end, the back 21 is provided adjacent one end, and upon its edges, with pins 75 24 or like projections, adapted to slide in the slots 9 of the back supports 8.

The manner in which the suspension members 6 are upheld, so as to provide a swinging movement for the chairs, is largely immaterial. If desired, the upper ends of the 80 suspension members 6 may be connected with a frame 25 of any desired sort, by means of the pivot elements 26.

Presupposing that the parts are positioned 90 as shown in Fig. 1, the operation of the device is as follows: The removable slats 4 of the frame 1 are displaced from the notches 5, these slats 4 being terminally supported by the seats 10, as shown in Fig. 95 3. The lower ends of the backs 21 are then seized, and pulled inwardly, the pins 24 riding downwardly in the slots 9 of the back supports 8, until the backs 21 are disposed in approximate parallelism with respect to 100 the seats 10, the backs 21 resting upon the removable slats 4, as shown in Fig. 3, so as to form a couch. Obviously, if desired, the pins 24 may be permitted to rest in the lower ends of the slots 9, the free ends of the backs 21 being swung upwardly. Under such circumstances, as clearly shown in Fig. 4, the slats sides 23 of the backs 21 will be outwardly disposed. It is thus possible to 105 present, for wear, either an upholstered surface, or a more efficient, wear-resisting surface, as the operator may desire. When the

backs 21 are positioned in alinement with the back supports 8, the lower ends of the backs will be engaged by the stops 20.

Having thus described the invention, what is claimed is:—

In a swing having oppositely disposed chairs, each comprising back supports and a seat, there being guides in the back supports; backs having members engaged in the guides; and removable elements adapted to be placed upon the seats to bridge the space between the seats; said members being downwardly movable in the guides and pivotally

operable therein to permit the backs to rest upon the removable elements; the guides converging downwardly to advance the backs longitudinally of the removable elements, thus to hold the edges of the backs in abutment between the seats.

In testimony that I claim the foregoing as my own, I have hereto affixed my signature in the presence of two witnesses.

WILLIAM ARCHER BORUM.

Witnesses:

ROBT. POWELL,
ELIZABETH BARRIER.
